JOSEPH A. KENNEDY, OF PAWTUCKET, RHODE ISLAND, ASSIGNOR TO CHERNACK MANUFACTURING COMPANY, OF PAWTUCKET, RHODE ISLAND, A CORPORATION OF RHODE ISLAND.

TENSION DEVICE FOR LOOMS.

1,333,808.

Specification of Letters Patent. Patented Mar. 16, 1920.

Application filed June 27, 1916. Serial No. 106,132.

To all whom it may concern:

Be it known that I, JOSEPH A. KENNEDY, a citizen of the United States, residing at Pawtucket, in the county of Providence and State of Rhode Island, have invented new and useful Improvements in Tension Devices for Looms, of which the following is a specification.

The present invention relates to a tension device for the threads used in weaving fabrics in a loom. The form of the invention herein illustrated has been designed particularly for use upon the shuttle of a circular loom to control the tension of the filling thread. While such form or embodiment is thus evidently well adapted for use upon the particular type of loom and the particular part of the loom indicated, nevertheless I do not limit my invention to a device adapted only for that use, since the principles of the invention may be applied, with or without material modification in the mechanical embodiment of said principles, to other parts of a circular loom, or to other types of loom, and indeed to other kinds of machine where it is desired to put a regulated and uniform degree of tension upon the thread or line. Accordingly my invention relates broadly to tension devices for threads or lines, wherever applied. The features and improvements in which the invention particularly consists appear from the following description of the particular device illustrated in the drawing, and from the appended claims. It may be said, however, that I consider the invention to consist both in the tension device itself, independently of the shuttle or other machine element with which it is used; and also in the combination of the device with a shuttle.

In the drawings,

Figure 1 represents a plan view of a shuttle for a circular loom having a tension device embodying my invention applied to it, and showing also the relation of the shuttle and tension device to the point around which the circular weaving action of the loom takes place.

Fig. 2 is a plan view of the tension device on a larger scale than that illustrated in Fig. 1.

Fig. 3 is an elevation of the tension device.

Fig. 4 is a perspective view of the device. Figs. 5 and 6 are views similar to Figs. 55 2 and 3 showing a modification.

The device itself consists essentially of a base plate *a*, a spring *b* and a number of pins or studs rising from the base plate. In the particular device here shown I have 60 provided eight of such pins and have here designated them respectively by the numbers 1, 2, 3, 4, 5, 6, 7, and 8. It is within my contemplation, however, to provide more or fewer pins than the exact number here 65 shown.

The part *b* which I have above designated as a spring is a flat strip of resilient metal, preferably tempered steel, which is held at one end against the surface of the base by a 70 screw *c*. The surface against which the spring is so held is that surface from which the pins rise. All other parts of the spring are free, being pressed toward the base only by such pressure as is transmitted from the 75 holding screw by the elasticity and resilience of the spring. The outer end *b'* of the spring is turned up to make it an easier matter to slip a thread under it. I have called part *b* a spring because mechanically 80 it is a piece of spring metal or a spring strip. Functionally, however, it is a presser adapted to bear with a resilient pressure uniform in quality and of practically a known intensity against the thread which is affected by 85 the tension device so as to make an initial tension in the thread by the friction caused by its pressure upon the thread and the pressure of the latter against the base.

For the purpose of illustrating a use of 90 the tension device I have shown the shuttle of a circular loom having a base *d* and a frame *e* on which are mounted the trunnions *f*, *f* of a bobbin *g* carrying a roll of thread or yarn *h*. The shuttle is mounted upon a 95 trackway in a circular loom and is propelled by a mechanism provided for that purpose in the loom, of which there are a number of well known commercial types, to travel in a circuit about a mandrel *k* which establishes what is called the weaving point of the loom. The lines marked *l* radiating from the weaving point represent warp threads with which the shuttle thread *h* is 100 interwoven. Fig. 1 also shows additional 105 shuttle threads *h'*, *h''* and *h'''* which are to be

understood as being supplied from a like number of other shuttles similar to the shuttle shown.

It will be seen that the tension device 5 is located on the shuttle frame between the bobbin and the weaving point. The shuttle thread is passed between the spring or presser *b* and the base of the tension device, passing thence in a more or less zigzag 10 course across and partly around two or more of the pins, finally passing from the pin 8, the last pin of the series, to the weaving point. For illustration I have shown the thread as passing in a sinuous course around the 15 pins 1, 6, 2, 7, 3, and 8 in succession. I may, however, pass it around other pins in other ways. A comparatively large number of pins are provided and are given a staggered arrangement so as to permit a great variation 20 in the course of the thread. By this means practically any desired tension may be caused in the thread, from that in which the thread is almost slack, to one where it is held firmly enough to break. The presser 25 *b* causes an initial drag on the thread whereby the bending of the thread thereafter around any pin causes it to exert a certain friction-producing pressure against the side of the pin. This pressure is increased with 30 every additional pin around which the thread is bent. The pins are made as nearly as possible alike with smooth sides and equal diameters in cross section. Thus all are able to exert substantially the same friction 35 on the thread, and thereby the number of pins about which the thread is bent is approximately a measure of the total drag applied by the tension device to the thread; so that by bending the thread about one, two, 40 three, or more of the pins the tension may be made of almost any exactly known and predetermined amount.

The initial drag caused by the spring presser *b* upon the thread may be varied according to the distance of the thread from the holding clamp *c* of the presser. That is, the spring presses with a greater force near its clamped end than near its free end, and the pressure thus applied at any point is proportional to the distance of the point from the secured end. Thus by bringing the thread past the presser tangent to the pin 6, for instance, instead of to the pin 5, as here shown, the spring is caused to bear 55 with greater force against the thread than in the arrangement shown in the drawings. The thread may be drawn across the presser at almost any desired distance from the holding screw *c* by appropriately choosing 60 the pin with which it is first brought into contact and laying its further course appropriately to maintain it in such contact.

The screws *m* and *n* shown in Figs. 1 and 2 are the means shown for securing the 65 tension device to the shuttle frame. Their

heads are set in countersunk holes flush with the upper surface of the base, so that they have no function in applying tension to the thread and oppose no obstacle to its movement.

The modification shown in Figs. 5 and 6 differs from that hereinbefore described in that the presser is constructed and mounted so as to permit knots in the thread to pass. This presser is designated *b*¹⁰ and consists 70 of a bar mounted upon two posts *p*—*p* which pass through holes in the presser bar near the ends of the latter and are firmly set into the base *a*. Springs *r* coiled about the posts force the presser toward the base, reacting 75 against a stop bar *s* which is fixed to the upper ends of the posts *r*. Such stop bar is merely one form of abutment and may be considered as typical of any sort of abutment for these springs. In the first form 80 shown the bar *s* is of such length that one end *s'* is carried on an incline toward the base plate and terminates at the end *a'* of the latter. This end is the advancing end 85 of the tension device when the latter is applied to a shuttle, and the inclined part *s'* of the stop bar then serves as a spreader to guide the warp threads over the ends of the posts *p* so as to clear the latter.

The side of the presser *b*¹⁰ is rounded or 90 beveled away from the surface of the base over which the thread passes, and the adjacent edge of the base is oppositely beveled or rounded at *a'*, thus providing a wide mouth and converging guiding surfaces between 95 which the thread passes before reaching the point at which it is pressed upon by the presser, such mouth being sufficiently wide to admit knots in the thread. Thereby it is made possible to tie the end of the thread 100 from an exhausted bobbin to the thread on a filled bobbin and continue weaving, saving the waste of thread which has hitherto been unavoidable with each change of bobbins. The knot connecting the two ends passes 105 between beveled surfaces on the base and the presser, whereby it is able to lift the presser and to pass it without being caught. The form of the pins around which the thread subsequently passes, already described, is 110 such that they do not impede the travel of a knot.

What I claim and desire to secure by Letters Patent is:

1. A tension device comprising a base, a plurality of guide members rising from said base adapted to guide thread in a sinuous course around and between them and over the base, and a presser urged resiliently toward the base and adapted to bear on the thread, applying an initial tension thereto; different parts of said presser being adapted to apply different degrees of pressure, and certain guide members being arranged in lines perpendicular to said different parts, 120 125 130

whereby to cause the thread to be pressed upon by one or another of such different parts according as the thread is brought into engagement first with one or another 5 of said guide members.

2. A tension device comprising a base, a number of studs rising from said base between and around which thread drawn over the base may be passed in a sinuous course, 10 and means for applying an initial tension to such thread consisting of a presser extending athwart the line in which the thread is led to the first of the studs to be engaged and yieldingly pressed toward the 15 base, between which and the base the thread passes; the studs being distributed beside the presser and generally lengthwise thereof, and the presser being adapted to exert progressively greater force from one end to 20 the other, whereby to apply greater or less initial tension according as the thread first passes to one or another of the studs.

3. A tension device comprising a base, a number of studs rising from said base 25 adapted to be engaged successively by a thread passing over the base and arranged to permit such thread to be first engaged with different particular ones of said studs, and means for applying tension to such 30 thread in its course to one of the studs, said means being constructed and adapted to cause such tension to be greater or less according to the position of the particular stud to which the thread passes therefrom.

35 4. A tension device for thread comprising essentially a base and a plurality of guide members projecting from said base adapted

to guide thread in a sinuous course and thereby to be pressed upon by the thread in a manner such as to exert a frictional resistance to the passage thereof, said guide members having smooth surfaces to engage the thread and being all alike, whereby the number of such members with which the thread is passed in contact serves as a measure of the tension applied to the thread, and a resilient presser arranged to press the thread against the base before the thread comes into engagement with said guide members and constructed to exert pressure 50 with different force at locations in line with different guide members.

5. A tension device comprising a base, a flat spring lying upon said base and clamped thereto at one end, between which and the 55 base thread is adapted to pass, and said spring exerting force against the thread thus passing according as the thread is nearer to or more remote from the clamped end of the spring, and a number of studs 60 rising from said base in position to permit such thread to be passed between and around them after passing said spring, and the studs being further arranged in lines of draft of the thread more or less distant from 65 said clamped end, whereby to permit of the thread being first engaged with different particular studs, and thereby to be pressed upon by different specific parts of the spring. 70

In testimony whereof I have affixed my signature.

JOSEPH A. KENNEDY.
